UNITED STATES PATENT OFFICE.

KARL EGGART, OF ARBON, SWITZERLAND, ASSIGNOR TO THE FIRM OF ADOLPH SAURER, OF ARBON, SWITZERLAND.

JACQUARD-CARD-PERFORATING MACHINE.

1,104,641.

Specification of Letters Patent.

Patented July 21, 1914.

Application filed March 14, 1913. Serial No. 754,195.

To all whom it may concern:

Be it known that I, KARL EGGART, a subject of the Emperor of Germany, residing at Arbon, Switzerland, have invented new and useful Improvements in Jacquard-Card-Perforating Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 In the manufacture of jacquard cards for embroidery machines there are two types of machines commonly employed, viz. punching machines for originals and copying machines. In both machines a paper strip, the so-called jacquard card, is provided with holes by perforating according to a definite system. The mechanisms of the two types of machines are similar, but in the first mentioned machine the originals of the 20 jacquard cards are perforated, while in the second mentioned machine such originals are copied.

25 The present invention relates to improvements in such machines, with a view to rendering the construction as simple as possible. Simplicity of structure is of great importance in such machinery, since the want of precision and other defects due to the mass of the oscillating parts, their wear, friction 30 and connection, can be diminished by reducing the mass. Moreover the work of the machine attendant is rendered easier.

35 By means of the present improvements exceedingly smooth working of the perforating machine is attained, and as a consequence an extremely beautiful embroidery can be produced; for the quality of jacquard embroidery depends upon the absolute correctness of the jacquard card, and this again 40 upon the simplicity of the machine with which it is produced.

45 A preferred embodiment of my invention is illustrated in the accompanying drawing, the machine shown being a punching machine with two pairs of perforated drums, of the character described in a pending United States patent application, Hippolyt Saurer, Serial No. 660,267 filed Nov. 14, 1911. Parts not necessary for a clear under-

standing of the present invention have been omitted.

In the drawing Figure 1 is a view in vertical section through the punching mechanism, and Fig. 2 is a plan view of the parts shown in Fig. 1, partly in section; while Figs. 3-6 are vertical sectional views showing the sliding needle frame in various positions.

5 T, T₁, T₂, T₃ are the four drums of the punching apparatus, operating in two cycles. T, T₁ are the drums for selecting or setting the needles e for the production of these holes in the card which are to cause vertical motion of the embroidering frame of the jacquard embroidery machine, while T₂, T₃ are the drums for selecting or setting the needles e¹ for the production of those holes in the card which are to cause horizontal motion of the frame. The coöperation of the drums T, T₁ with the needles e, 65 is substantially the same as that of the drums T₂, T₃ with the needles e¹. W, W¹ are feed rollers for advancing the card strip K. The roller W¹ is driven with intermittent positive motion in any suitable manner. 70 M is the stationary bottom or bed die over which the card strip K travels.

75 a is a punch support or carrier, which is vertically reciprocable in guides 1, 2 by means of levers 3, 4, actuated by a shaft 5 which is rocked by any suitable well known means. The punches b are loosely suspended by their heads in the support a, there being a punch b provided below each needle e, and each needle e¹. In the support a there 80 is mounted the frame d, in which are loosely slidable the needles e, e¹, the underside of each of which is recessed at x, z, so as to leave an intermediate tongue y. The frame d is slidable horizontally to and fro by levers 6, 7, actuated by the shaft 8, which like the shaft 5 is oscillated at intervals by any appropriate means.

85 The operation of the machine is as follows: The two drums T, T₂ are first set, according to the desired length of the stitch, in the manner disclosed in the United States patent application Ser. No. 660,267, already referred to. Hereupon the frame d is moved toward the left by the levers 6, 7, whereby 90 the needles e, e¹ are set, according to the position of the drums T, T₂. If the needles e, e¹ are in alinement with holes in the drums 95

T, T², they will enter the latter and thus will not be shifted in the frame d. Should the needles e, e¹, however, lie opposite unperforated parts of the drums, T, T², they 5 will contact with the drum surface and thus will be pushed toward the right in the frame d. Thus through the motion of the frame d toward the left, the needles e, e¹ are set, corresponding to the positions of the drums T, 10 T². By rocking the shaft 8 the frame d is next drawn back into its central position, the needles e, e¹ maintaining their assumed position relatively to the frame. Fig. 4 shows in the central position of the frame 15 d a needle e which has not been shifted by the drum T, while Fig. 5 is a like view showing a needle e which has been moved by contact with an unperforated part of the drum surface. In the case of those needles 20 e, e¹ which have not been shifted, the tongues y are located above the punches b, as shown in Fig. 4; while in the case of those needles e, e¹ which have been moved by contact with the drum surface, the recesses x are located 25 above the punches b, as Fig. 5 shows. If then, by rocking the shaft 5 the support a is moved downward, those punches b above which tongues y are located will perforate holes in the card K, while those punches 30 above which recesses x are located only rest lightly upon the card, receding upward into the recesses x as the support descends, so that no holes are pierced. Hereupon the support a rises into its normal position 35 again, and the frame d will, through the short oscillation of the shaft 8 be drawn toward the drums T¹, T², (see Fig. 6), whereupon the procedure is repeated. The needles e, e¹ may also be so formed that it is 40 the pushed needles which bring their punches into operation, while the unpunched ones allow their punches to recede in upward direction. The machine might likewise be constructed to operate in a single 45 cycle, only two drums (e. g., T, T²) being employed. In such construction the needles are naturally only set at one side, and a device is provided to return all the needles to their normal position again. The needle 50 frame is, in such a machine, pushed out of its normal position in one direction, and the needles are therefore only furnished with a single recess x or z.

What I claim as new is:

55 1. In a jacquard card perforating machine, selecting means, a support or carrier, means to move the same toward and from the card to be perforated, a frame movable

in the support or carrier at right angles to the direction of movement thereof and needles movable by the selecting means in the frame. 60

2. In a jacquard card perforating machine, a frame, needles slidable therein, a support in which the frame is slidably mounted, punches slidable in the frame, and means for moving the support to and from the work. 65

3. In a jacquard card perforating machine, a frame, needles slidable therein, a support in which the frame is slidably mounted, punches slidable in the frame, means for setting the needles in the frame, and means for moving the support to and from the work. 70

4. In a jacquard card perforating machine, a rotatable drum, a frame, horizontal needles slidable in axial direction therein, a support in which the frame is mounted with capability of sliding in horizontal direction, 80 vertical punches axially slidable in the frame below the needles, means for moving the frame to and from the drum, and means for moving the support to and from the work. 75

5. In a jacquard card perforating machine, a rotatable drum, a frame, horizontal recessed needles slidable in axial direction therein, a support in which the frame is mounted with capability of sliding in horizontal direction, a vertical punch, axially 90 slidable in the frame, located below each needle and adapted to enter the recessed part of the latter, means for moving the frame to and from the drum, and means for moving the support to and from the work. 95

6. In a jacquard card perforating machine, two parallel shafts, a drum loosely mounted on each shaft, a frame located between the two drums, horizontal needles slidable in axial direction therein and presenting two recesses in their lower edge, a support in which the frame is mounted with capability of sliding in horizontal direction, a vertical punch axially slidable in the frame, located below each needle and adapted to enter the recesses in the latter, means for moving the needle frame to and fro between the drums, and means for moving the support to and from the work. 100

In testimony that I claim the foregoing 110 as my invention, I have signed my name in presence of two subscribing witnesses.

KARL EGGLART.
